Primary Examiner — Ricky Pham(74) *Attorney, Agent, or Firm* — Law Office of Robert M. Patino(57) **CLAIM**

The ornamental design for a cutting board connector, as shown and described.

DESCRIPTION

FIG. 1 is a top front perspective view of a cutting board connector showing my new design;

FIG. 2 is a top plan view thereof;

FIG. 3 is a bottom plan view thereof;

FIG. 4 is a left-side plan view thereof;

FIG. 5 is a right-side plan view thereof;

FIG. 6 is a front-side plan view thereof; and,

FIG. 7 is a rear-side plan view thereof.

The broken lines shown in the drawings are for illustrative purposes only and form no part of the claimed design.
